United States Patent Office

Des. 188,509
Patented Aug. 2, 1960

188,509

KNOB

La Verne E. Clayton, Rockford, Ill., assignor to Amerock
Corporation, Rockford, Ill., a corporation of Illinois

Filed Apr. 4, 1960, Ser. No. 60,152

Term of patent 14 years

(Cl. D50—3)

Fig. 1

Fig. 2

Fig. 3

Figure 1 is a top-view of a knob showing the new design of the present invention.

Fig. 2 is a front elevational view of the knob.

Fig. 3 is an enlarged sectional view taken along the line 3—3 in Fig. 2.

I claim:

The ornamental design for a knob, substantially as shown.
